DIRECTION FINDING COIL ANTENNA

August Leib, Berlin, Germany, assignor to Telefunken Gesellschaft fur Drahtlose Telegraphie m. b. H., Berlin, Germany, a corporation of Germany

Application April 23, 1930, Serial No. 446,477
In Germany June 8, 1929

3 Claims. (Cl. 250—11)

In direction-finding work by the aid of a frame or coil aerial, recourse is usually had to a non-directional auxiliary antenna for the purpose of determining the sense of direction of the incoming signals. However, the use of the latter is liable to be attended with undesirable complications in that the same acts like a body reflecting the electromagnetic radiations and this in turn occasions a certain angular displacement or shift 10 of the plane of the waves falling in the directional antenna.

It has been suggested in the prior art to mount the auxiliary antenna in the axis of rotation of the direction-finding frame antenna (see, for example, Keen, "Wireless Direction Finding", second edition, page 113, Fig. 106 and page 116, lines 15 6 and 5 from below). However, even in this scheme mutual influences between the two antennae are not entirely precluded inasmuch as then mutual electrostatic actions occur on account of the proximity of the two antennae.

Now, according to this disclosure, perfect cooperation of the direction-finding antenna and the auxiliary antenna or auxiliary antenna lead 25 disposed in the axis of rotation thereof is made possible by that for the purpose of insuring protection from mutual influences, a grounded metal tube or pipe, or some similar metal protection means, is provided between the auxiliary antenna lead and the windings or leads of the directional antenna.

In case the direction-finding antenna is enclosed within a weather-proof pipe, the latter could be used as the auxiliary antenna or antenna lead.

In order that also the lightning protection means may be arranged as symmetrically as feasible in relation to the directional antenna, it is a particularly advantageous scheme to employ the said weather-proof pipe as one pole of the lightning protection device.

The invention will be better understood by reference to the drawings throughout which like reference numerals indicate like parts and in which,

Figure 1 shows a wiring diagram of the antenna arrangement according to this invention;

Figure 2 shows in elevation, the weather-proof frame aerial, the vertical aerial associated therewith, a static electricity protection device, the mounting for the frame aerial, a receiver and the shield enclosing the leads from the frame aerial to the receiver;

Figure 2a shows a cross section taken along the line A, B of Figure 2.

Figure 2b shows a cross section taken along the lines C, D of Figure 2;

Figure 3 shows in prospective an application of the present invention; while,

Figure 3a shows a modification of the arrangement shown in Figure 3.

Fig. 1 of the drawings shows a fundamental key diagram of the arrangement according to this invention. Referring to the drawings, *a* denotes the auxiliary antenna which is neutralized (uncoupled) in relation to the supply leads 1, 2, 3, 4, of the coil aerial by means of a grounded metal protection means *E*. The coil aerial consists, for instance, of two coil windings *R*₁ and *R*₂ which may be connected in series or in parallel according to requirements.

Fig. 2 shows an elevation of the arrangement according to this invention in combination with a weather-proof direction-finding antenna, the weather-proof pipe of which at the same time serves as one pole of the lightning protection device. *a* here denotes the weather-proof protector pipe of the directional aerial. The position of the winding of the directional antenna inside said protective pipe is shown by way of example for the section A—B in Fig. 2a. *c* denotes the shaft pipe assembled together with the frame ring *a* by means of a holding clip *b*. The position of the leads inside said shaft is shown, for instance, in Fig. 2b for the section C—D. The numerals 1—6 here refer to the key diagram Fig. 1. *d* is the coupler fork of the hand wheel secured upon the shaft by the aid of a clip. *e* denotes the drive of the directional aerial comprising hand-wheel and goniometer scale or dial. *f* is a flexible metal protection means the cross-section of which is the same as shown in Fig. 2a. *g* is a coupler plug uniting all of the leads 1—6 shown in the key diagram, *i* is the direction-finder receiver with which the direction finding or auxiliary antenna may be connected by inserting the plug *g* in the receptacle bushes disposed in the plate *i*. *k* is the auxiliary antenna lead. It may be identical with the auxiliary antenna *A* when the latter constitutes a simple linear structure (see Fig. 3), or else it may serve as the lead brought to the auxiliary antenna consisting, for instance, of two diagonal wires *A*₁, *A*₂, and being disposed in horizontal sense (Fig. 3). *l* is an auxiliary fixture for connecting the auxiliary antenna and for clamping the insulator piece *p* of the frame ring, *m* denotes the connecting lead between *l* and the lead of the auxiliary antenna accommodated inside the pipe shaft *c*.

n are the lightning protection horns adapted to 55

conduct a lightning stroke that has struck the antenna from the frame to earth.

As can be seen from Fig. 2b, the lead 5 of the auxiliary antenna is disposed inside a ground 5 metal protector sheath 6 so that it is perfectly screened from the adjacent leads 1-4 of the directional antenna.

I claim:

1. In a directional aerial system the combination, of a frame aerial, a conducting closure member therefor, a vertical aerial supported by said closure member symmetrically with respect to said frame aerial, electrical disturbance protective means cooperating with said vertical aerial 15 and said closure member to protect said vertical aerial from electrical disturbances and a receiver adapted to be connected to said aerial system.

2. In a directional aerial system the combination, of a frame aerial, a conducting closure

member therefor, a vertical aerial supported by said closure member symmetrically with respect to said frame aerial, disturbance protective means associated with said vertical aerial and said closure member, a receiver adapted to be connected to said aerial system, and shielding means for the leads between said system and said receiver including means for isolating the vertical aerial connection.

3. A direction finding system including a rotatable frame aerial, shielding means therefor, a vertical aerial mounted on said frame aerial, an electrical disturbance dissipating means mounted on said frame aerial adjacent said vertical aerial, a receiver, means for connecting said frame aerial to said receiver, and a symmetrical connection between said vertical aerial and said receiver.

AUGUST LEIB.
